Fig. 4.

Fig. 5.

FIG. 1 is a front view of an overhead cabinet for condiments or the like embodying my new design, the door frame portions being here shown for illustrative purposes only.

FIG. 2 is a perspective view taken from the front, top and one end of the cabinet, here showing the door in an open position.

FIG. 3 is a perspective view taken from the front and bottom of the cabinet.

FIGS. 4 and 5 are fragmentary sectional views taken as indicated by lines 4—4 and 5—5 on FIG. 3, and illustrating the detailed characteristics of the cabinet.

The essential features of my design reside in the portions shown in full lines. The right side is substantially the same as the left side shown and the horizontal broken lines and the stippling on the front are intended to show contrast.

I claim:

The ornamental design for an overhead cabinet for condiments or the like, as shown and described.
